Primary Examiner — Catherine R Oliver-Garcia(74) *Attorney, Agent, or Firm* — Fox Rothschild LLP(57) **CLAIM**

The ornamental design for a knife and sheath, as shown and described.

DESCRIPTION

FIG. 1 is a top, front, right perspective view of a knife and sheath according to the present disclosure.

FIG. 2 is a front view of the knife and sheath of FIG. 1.

FIG. 3 is a rear view of the knife and sheath of FIG. 1.

FIG. 4 is a left view of the knife and sheath of FIG. 1.

FIG. 5 is a right view of the knife and sheath of FIG. 1.

FIG. 6 is a top view of the knife and sheath of FIG. 1; and,

FIG. 8 is a top, front, left perspective view of the knife and sheath of FIG. 1.

The broken lines depict environmental structure and are for illustrative purposes only and form no part of the claimed design.
